DUAL PURPOSE BANKING ENVELOPE
Robert D. Cousins, Jefferson County, Ky., assignor to
Curtis 1000, Inc., St. Paul, Minn., a corporation of
Minnesota

Filed Oct. 8, 1963, Ser. No. 314,664
5 Claims. (Cl. 229—72)

This invention relates to banking envelopes and is especially concerned with an envelope which is equally well suited for either postal banking or auto banking.

In postal banking a customer ordinarily places his checks, deposit slips, etc., in a special folder or envelope, which he then encloses in a second envelope and mails it to the bank. The bank removes the contents of the folder, inserts a receipt or other appropriate papers, encloses the folder in a second envelope, and returns it to the customer.

A common type of bank-by-mail envelope is formed from a rectangular sheet of paper folded in the center and sealed at one edge, being open at the left end and the top to permit insertion of checks, deposit slips, customer identification card, currency etc. In order to make the contents of the folder visible, a hole is often drilled through the two major panels of the folder. The customer inserts the folder in a pre-addressed envelope provided by the bank (e.g., a No. 9); the bank returns the folder and another envelope to the customer in a larger window envelope (e.g., a No. 10) with the folder so positioned that the customer's name, printed on one face of the folder, is visible.

In drive-in banking, a customer conducts his banking business from his car window, enclosing checks, bills, change and a deposit slip in another special envelope and handing it to the cashier. The cashier removes the envelope contents, replaces them with a receipt and/or funds, as is appropriate to the circumstances, and returns the envelope.

A drive-in banking envelope typically has a currency recess, a coin pocket, and a flap which closes the coin pocket and locks behind the currency recess; drive-in envelopes of this type are described and claimed in Whitman U.S. Patents No. 2,863,599 and 2,936,945 and Clegg U.S. Patent No. 3,043,493. In the envelopes described in the Whitman patents, the flap is detachable and substantially the same size as the body of the envelope, serving as a deposit slip. Although extremely useful in drive-in banking, these envelopes suffer from the fact that they can be used only once. Additionally the detachable deposit slip-flap is unduly large for convenient insertion behind the currency panel. Accordingly, even though the pocket could be used to hold a customer's identification card, these envelopes have never proved attractive for use in postal banking. The closing flap on the envelope described in the Clegg patent is easy to lock in place, but the pocket is so large that identification cards are awkward to remove; this envelope, too, has thus not been used for postal banking.

I have now devised a unique re-usable envelope which is simple to fabricate and highly suitable for use in both postal and drive-in banking. As a result of this versatility, a bank may carry a smaller inventory of banking envelopes and needs to provide only one kind. Customers, who often do both postal and auto banking, may use this envelope for either purpose. My novel envelope is related

2

to the envelopes disclosed in the aforementioned patents, but differs in certain critical respects, as will be shown.

My invention is illustrated in the accompanying drawings, in which like numbers refer to like parts in the several views and in which:

FIGURE 1 illustrates a presently preferred envelope embodying my invention;

FIGURE 2 illustrates the blank from which the envelope in FIGURE 1 is formed;

10 FIGURE 3 illustrates the blank of FIGURE 2 is an intermediate stage of folding;

FIGURE 4 represents an alternate envelope embodying my invention;

15 FIGURE 5 shows a blank from which the envelope in FIGURE 4 is formed; and

FIGURE 6 shows the blank of FIGURE 5 in an intermediate stage of folding.

Referring now to FIGURES 1-3, back panel 10 is adjoined at the right edge by end panel 11, at the bottom by front panel 12, and at the top by flap 14. Tab 13 adjoins both front panel 12 and end panel 11. The front face of the distal portion of end panel 11 is provided with a gummed area 15, and the back surface of tab 13 is provided with a similarly gummed area 16.

25 In forming the envelope shown in FIGURE 1 from the blank shown in FIGURE 2, end panel 11 is folded to the left over panel 10, to which it is adhered by gummed area 15. Simultaneously tab 13 is folded over front panel 12, thereby creating the intermediate product

30 illustrated in FIGURE 3. Front panel 12 is then folded upward over back panel 10 and end panel 11 gummed area 16 of tab 13 being adhered to the face of end panel 11. The envelope of FIGURE 1 is thus so constructed that panel 10 and end panel 11 cooperate to form a pocket

35 in which coins may be placed. Likewise front panel 12 cooperates with back panel 10 and end panel 11 to form a recess 18 in which bills, currency, deposit slips, etc., may be placed. In postal banking, where it may be undesirable to mail coins, the pocket formed by end panel 11 and back panel 10 may contain a customer's identification card. In any event, flap 14 is folded over

40 pocket 18 and tucked behind front panel 12, which serves to hold it in place mechanically and prevent loss of the contents of pocket 18.

The specific construction illustrated in FIGURES 1-3 is subject to numerous variations, so long as certain critical facts are borne in mind. For example, front panel 12 is desirably constructed so that there is a viewing point 17 at which the upper left corner of smallest checks or

50 deposit slips placed in recess 18 should be visible. For most banking purposes this means that viewing point 17 should be located slightly less than 6 inches from the right edge of the envelope and slightly less than 2½ inches from the lower edge of the envelope. Expressed in another way, the distance from viewing point 17 to the bottom of the envelope should ordinarily be on the order of ½ to ⅔ the height of back panel 10. The height of front panel 12 throughout the remainder of the envelope may be the same as at viewing point 17, but

55 it is generally desirable to have this dimension nearly as great as the height of back panel 10, both to insure greater protection for currency and to provide a panel behind which flap 14 may be locked.

For maximum utility, i.e., so that the largest standard checks can also be accommodated, my novel envelope

is desirably constructed so that it is about $8\frac{1}{2}$ inches long and $3\frac{1}{2}$ inches high. For postal banking an envelope of this size may be enclosed in a No. 9 envelope; the customer's name and address are advantageously printed on the lower left portion of front panel 12 for use with a window envelope.

The distance which flap 14 extends beyond the fold line separating it from back panel 10 is also related to the overall size of the envelope and to the height of front panel 12 in the area where flap 14 is situated. I have found, for example, that the height of flap 14 should ordinarily be at least $1\frac{1}{2}$ inches in order to retain coins in pocket 18. Likewise, I have found that the height of flap 14 should be such that when folded behind front panel 12 the distance from the distal portion of flap 14 to the bottom of the envelope is less than $2\frac{1}{2}$ inches, so that the top of bills or small checks may be covered by flap 14. For ease in manipulating flap 14, however, the sum of (1) the height of flap 14 and (2) the distance from the top of front panel 12 to the bottom of the envelope should generally be in the range of $5/4$ to $3/2$ the height of back panel 10. It will thus be seen that if front panel 12 does not extend to the top of back panel 10, it is desirable that the height of flap 14 be somewhat greater.

If desired, flap 14 may extend the full length of back panel 10; in such case, however, the shapes of flap 14 and front panel 12 should be so coordinated that there will be some point 17 where bills and small checks can be seen after flap 14 is closed.

Referring now to FIGURES 4-6, it will be noted that back panel 40 is adjoined on the left by end panel 41, which has a gummed area 45 along its distal portion. Front panel 42 adjoins the lower edge, and flap 44 adjoins the upper edge, of back panel 40. Tab 43 adjoins the right edge of panel 40.

In forming the envelope shown in FIGURE 4 from the blank shown in FIGURE 5, end panel 41 is folded over the face of back panel 40, gummed area 45 adhering the two panels together to define a currency- or deposit card-carrying pocket 48. Flap 43 is bent forward over the face of panel 40, thereby exposing gummed area 45. Front panel 42 is then folded up over pocket 48, the right edge of front panel 42 being adhered to gummed area 46 so as to define a currency recess 49 having closed bottom and right edges and open top and left edges.

In the embodiment shown in FIGURES 4-6 pocket 48 is located at the left end of the envelope, thus, a normally right-handed person finds it convenient to use pocket 48. Since, however, the open end of the envelope provides no aid in holding down flap 44, flap 44 must extend far enough toward the right that is may be locked into position behind front panel 42. In so doing, as previously indicated, viewing point 47 should be so positioned that the upper left edge of small checks or bills is visible.

The two embodiments of my invention just discussed are, as indicated, subject to numerous variations without departure from the spirit of my invention. Thus, tabs 13 or 43 may be eliminated, front panels 12 or 42 being correspondingly directly adhered to the back panels 10 or 40. Likewise, pocket 48 shown in FIGURES 4-6 may be positioned on the right end of the envelope, as illustrated in FIGURES 1-3. If desired, a pocket may be formed at each end of the envelope.

What I claim is:

1. A banking envelope, suitable for both drive-in and postal banking, comprising.

a rectangular back panel having a length of at least about $8\frac{1}{2}$ inches and a width of at least about $3\frac{1}{2}$ inches,

a substantially rectangular end panel adjacent one end of said back panel and positioned thereover, the height of said end panel being slightly less than the height of said back panel and the length of said end panel being on the order of one-half that of

5 10 15 20 25 30 35 40 45 50 55 60 65 70 75

4 said back panel, the end portions of said end panel being joined to transverse portions of said back panel, thereby forming a pocket suitable for containing either coins or a banking identification card, a front panel extending from the bottom of said back panel and folded over said back panel and said pocket, the length of said front panel being substantially the same as the length of said back panel, one end of said front panel being connected to the panel immediately therebeneath, thereby forming a bill- or check-receiving recess having a closed end and an open end, the height of said front panel at a point slightly less than 6 inches from said closed end being slightly less than $2\frac{1}{2}$ inches, a flap extending from the top of said back panel adjacent said closed end and folded over said pocket, the length of said flap being at least as great as the length of said pocket, the height of said flap at the portion adjacent said closed end being such that (a) the flap extends to at least slightly less than $2\frac{1}{2}$ inches from the lower edge of the envelope and (b) the combined height of said flap and said side panel is on the order of $5/4$ to $3/2$ the height of said back panel, the height of said flap at a point slightly less than 6 inches from said closed end being such that the combined width of said flap and said side panel is less than the width of said central panel, whereby said flap may be readily folded over said pocket and tucked behind said front panel over the contents of said recess to keep said pocket closed, the contents of said recess remaining visible, said flap being readily lifted to examine or remove the contents of said pocket. 2. The envelope of claim 1 wherein the closed end of said recess is at the same end of the envelope as said pocket. 3. The envelope of claim 2 wherein the width of said front panel at said closed end is only slightly less than the width of said back panel. 4. The envelope of claim 3 wherein the length of said flap is approximately equal to the length of said pocket. 5. A banking envelope, suitable for both drive-in and postal banking, comprising a rectangular back panel, a substantially rectangular end panel extending from the right end of said back panel and folded thereover, the height of said end panel being slightly less than the height of said back panel and the length of said end panel being on the order of one-half that of said back panel, the distal portion of said end panel being adhered to a transverse intermediate portion of said back panel, thereby forming a pocket suitable for containing either coins or a banking identification card, a front panel extending from the bottom of said back panel and folded over said back panel and said pocket, the length of said front panel being substantially the same as the length of said back panel, the right end of said front panel being connected to the panel immediately therebeneath, thereby forming a bill- or check-receiving recess having a closed end and an open end, the height of said front panel at a point spaced from said closed end being such that the upper left corner of currency, positioned at the bottom and right of said recess, is visible, a flap extending from the top of said back panel adjacent said closed end and folded over said pocket, the length of said flap being at least as great as the length of said pocket, the height of said flap at the portion adjacent said closed end being such that (a) the flap extends to at least slightly less than the width of currency from the lower edge of the envelope and (b) the combined height of said flap and said

side panel is on the order of 5/4 to 3/2 the height of said back panel, the height of said flap at a point slightly less than the length of currency from said closed end being such that the combined width of said flap and said side panel is less than the width of said central panel, whereby said flap may be readily folded over said pocket and tucked behind said front panel over the contents of said recess to keep said pocket closed, the contents of said recess remaining visible, said flap being readily lifted to examine or remove the contents of said pocket.
